MEANS FOR DISPENSING THE CONTENTS OF COLLAPSIBLE TUBES

Clifford J. Nelson, Washington, D. C.

Application March 12, 1957, Serial No. 645,458

4 Claims. (Cl. 222—99)

This invention relates to the art of dispensing and more particularly to a collapsible tube having improved means thereon for dispensing the contents thereof.

The problem of dispensing collapsible tubes, such as toothpaste tubes or the like, is well known and one which is confronted daily by a large portion of the population of this country. The present tubes, as for example, the tubes containing toothpaste or the like, are not provided with any positive means for dispensing the contents thereof, but rely on the user to pinch or collapse the tube manually. It is well known that this procedure soon causes the tube to become bent and distorted intermediate its ends and these bends or distortions often result in breaks in the wall of the tube, resulting in a dispensing of the contents through the breaks. Moreover, where the contents of a collapsible tube are dispensed in this manner, there is considerable material left in the tube when dispensing is no longer possible.

There have been many proposals to provide a means for orderly and progressively rolling up the collapsed end of a collapsible tube so as to dispense the contents thereof as desired. These proposals have not been adopted, either because they have proven too expensive and complicated, or have required expensive modifications of the collapsible tube and cap itself. One problem in this regard is that the provision of a turning or winding means adjacent the collapsible end of the tube necessitates the addition of permanent lateral structure to the tube so that the same cannot fit within the close tolerance containers which are now in wide use.

Accordingly, it is an object of the present invention to provide an improved means for dispensing the contents of a collapsible tube which does not necessitate the addition of permanent lateral structure to the collapsed end of the tube so that the same can fit within a close tolerance container.

Still another object of the present invention is the provision of an improved means for winding the collapsed end of a collapsible tube so as to dispense the contents thereof, which means includes an improved spindle arranged to be mounted transversely on the collapsed end of the collapsible tube so that the latter can be wound therearound and improved means arranged to be removably carried by the cap of the tube so that it may be removed therefrom and engaged with the spindle to effect turning thereof.

Still another object of the present invention is the provision of a collapsible tube of the type described having improved means thereon for winding the collapsed end thereof so as to dispense the contents of the tube, which is simple in construction, easy to operate and economical to manufacture.

Still another object of the present invention is to incorporate the means within the symmetrical lines of the tube, preserving the attractiveness thereof and to provide the user of tube contents with such means as will encourage, indeed invite, the proper collapsing of the tube.

These and other objects of the present invention will

2

become more apparent during the course of the following detailed description and appended claims.

The invention may best be understood with reference to the accompanying drawings wherein an illustrative embodiment is shown.

In the drawings:

Figure 1 is a front elevational view of a collapsible tube embodying the principles of the present invention and showing the same in the condition in which it is packed;

Figure 2 is a view similar to Figure 1 showing the turning knob of the present invention in its operative position for winding the collapsed end of the tube, with the cap mounted on the dispensing head of the tube;

Figure 3 is a side elevational view showing the tube in a position to have the contents thereof dispensed by turning the winding knob;

Figure 4 is an enlarged exploded cross-sectional view taken along the line 4—4 of Figure 1, showing the turning element in elevation;

Figures 5 and 6 are progressive fragmentary perspective views illustrating the manner in which the winding spindle is secured to the collapsed end of the tube; and

Figure 7 is a component perspective view illustrating another embodiment of the present invention.

Referring now more particularly to the drawings, there is shown a collapsible tube 10 of conventional construction, such as is utilized for dispensing toothpaste, paint and the like. The tube includes the usual tubular body, having a dispensing head 12 formed on one end thereof and the opposite end collapsed, as indicated at 14, so as to permanently close the same after the tube has been filled. The dispensing head 12 is exteriorly threaded to receive a cap 16, which controls the dispensing. It will be understood that the above construction is completely conventional and forms no part of the present invention, except insofar as it is modified and combined with the features thereof hereinafter described to form an operative combination.

The present invention is more particularly concerned with an improved means for dispensing the contents of the collapsible tube. To this end, there is provided an elongated spindle 18 having a longitudinally extending slot 20 formed therein and extending from one end thereof to a point spaced inwardly from the opposite end thereof.

The spindle 18 is arranged to be mounted in transversely disposed relation on the collapsed end 14 of the tube 10 and has a length which is not greater than the width of the collapsed tube end 14. In order to secure the spindle to the collapsed tube end 14, the latter is provided with a cutout portion 22, which is formed in one side of the collapsed end 14, as shown in Figure 5. The spindle 18 is mounted on the collapsed end by engaging the remainder of the collapsed end adjacent the cutout 22 within the longitudinal slot 20. In this regard, it will be noted that the remaining portion of the spindle will be disposed wholly within the cutout portion 22 so that the mounting of the spindle on the collapsed end 14 of the tube does not add permanent structure which extends laterally beyond the sides of the collapsed end.

The end of the spindle remote from the slot 20 has an aperture 24 extending longitudinally therein. Preferably, this aperture is interiorly threaded to receive a threaded stem 26 projecting from a turning element 28. The turning element 28 is removably mounted in the cap 16 and, to this end, the latter is provided with a longitudinally extending threaded aperture 30 within which the threaded stem 26 may be engaged. As shown in Figure 4, it will be noted that the aperture 30 extends longitudinally downwardly from the top of the cap 16 but terminates short of the interior thereof. The turning element 28 may be of any suitable shape, but preferably is formed so as to provide a smooth extension of the upper end

of the cap. It will also be noted that the turning element is not of substantial longitudinal dimension so that it does not appreciably add to the overall length of the collapsible tube.

Referring now more particularly to Figure 7, there is shown a modified form of the invention in which the cap 16' and the slotted spindle 18' are provided with elongated apertures 32 and 34 respectively which correspond in shape to the shape of a bar 36 projecting from a turning element 28'. As shown, the bar is rectangular in cross-sectional configuration and of substantially uniform area throughout.

It will be understood that the exact projection-aperture structure utilized for engaging the turning element alternatively within the cap and the spindle may take many forms, the threaded stem 26 and bar 36 merely constituting two preferred examples of constructions that may be employed. In addition, the slot 20 may be formed in the intermediate portion of the spindle and the collapsed end of the tube provided with spaced cutout portions on each side thereof so that the portion intermediate the cutouts may be inserted within the slot. In this manner, an aperture may be formed in both ends of the spindle to alternatively receive the projection of the turning element.

In operation, the spindle and turning element of the present invention are mounted on the collapsible tube in the manner indicated in Figure 1. That is, the collapsed end of the tube is rolled or crimped around the spindle in the manner shown in Figures 5 and 6 and the turning element 28 is removably secured to the cap 16 by engagement of the threaded stem 26 within the threaded aperture 30. When it is desired to dispense the contents of the tube 10, the turning element 28 is removed from the cap by unscrewing the stem 26 from the aperture 30 and inserting it in the threaded aperture 24 at the end of the spindle 18, as shown in Figure 2. Next, the cap 16 is removed and the turning element manually moved so as to wind the collapsed end around the spindle which, in turn, effects dispensing of the contents of the tube outwardly through the uncapped dispensing head 12, as shown in Figure 3. The operation of the embodiment shown in Figure 7 is identical to that described above and it will be understood that the turning element 28' in this embodiment may be removed and inserted in the openings 32 and 34 by simple rectilinear motion, rather than in a turning motion, as is necessary with the threaded stem 26.

In this regard, it will be noted that the diameter of the turning element 28' is greater than the diameter of the adjacent portion of the cap so as to present a flange above the cap which may be easily grasped to effect the rectilinear motion necessary to remove the turning element from the cap. The threaded stem arrangement shown in Figures 1-6 lends itself more readily to the formation of a turning element having an exterior surface flush with the adjacent exterior surface of the cap since removal can be effected solely by a turning movement. The flush threaded stem arrangement is more desirable from the standpoint of appearance, while the bar arrangement is more desirable from the standpoint of simplicity of operation. Preferably, the diameter of the turning element is made sufficiently large so that it will be greater than the diameter of the collapsed end of the tube when the same is entirely rolled up. In this regard, the diameter of the spindle is preferably made as small as possible commensurate with the strength necessary to perform its winding function. A slender spindle enhances the appearance of the tube and more nearly approximates the conventional crimped end.

It can thus be seen that there has been provided an improved means for dispensing the contents of a collapsible tube which has many distinct advantages over the arrangements heretofore proposed. Of primary significance, is the fact that the spindle of the present invention

can be readily mounted on the collapsed tube end 14 without adding permanent structure, which extends laterally of the tube to thus increase its lateral dimension. This is important for the reason that the tubes presently utilized are arranged to fit closely within containers and the addition of permanent lateral structure would require the utilization of differently designed containers which would materially increase the cost of the packaged commercial article. Another advantage of the present invention is that the turning element is carried by the collapsible tube cap in such a way as to constitute an extension thereof, which enhances the attractiveness of the commercial article. If desired, the cap and turning element may both be provided with matching ridges or knurling, as is well known. The turning element may be readily removed from the cap and engaged with the spindle to effect a winding of the collapsed end of the tube.

The fact that the winding element is separate from the cap enables the user to effect a winding of the collapsed end of the tube, either while the cap is mounted on the dispensing head 12, as for example, when it is necessary to force out creases which have accidentally been formed in the tube wall, or, alternatively, the cap may be removed in the normal dispensing operation. Once the turning element has been mounted on the spindle, the cap may be simply removed when it is desired to dispense the contents from the tube. The dispensing is orderly and progressively accomplished by the winding of the collapsed end around the spindle by the turning of the element 28. This insures that all of the contents within the tube will be progressively squeezed out so that a minimum of residue material remains within the tube when dispensing is no longer possible.

The fact that the present arrangement enables the collapsed tube end to be wound around the spindle with the cap mounted on the dispensing head of the tube enables the winding procedure to be accomplished with an equal pressure on the tube wall. That is, with the cap removed, there is no counterpressure from the dispensing head and, hence, winding with the cap removed may create an uneven pressure in the wound end. The equal pressure obtained when winding with the cap on creates an equal pressure on the tube wall, thus retaining the symmetry of the tube wall, which, in turn, serves to prevent creases and wrinkles therein, the primary cause of wall failure. This equal pressure winding also facilitates uniform winding of the tube and serves to smooth out creases and wrinkles previously made through accident or other reasons.

It thus will be seen that the objects of this invention have been fully and effectively accomplished. It will be realized, however, that the foregoing specific embodiment has been shown and described only for the purpose of illustrating the principles of this invention and is subject to extensive change without departure from such principles. Therefore, this invention includes all modifications encompassed within the spirit and scope of the following claims.

60 I claim:

1. In a collapsible tube having a collapsed end, a dispensing head on its opposite end and a cap removably mounted on said dispensing head for closing the same; the improvement comprising means secured transversely across the collapsed end of said tube around which the latter can be wound, said means having a length not greater than the width of said collapsed tube end so as to permit said tube with said means secured thereto to fit within a close tolerance container arranged to fit said tube without said means secured thereto, and means removably carried by said cap adapted to be connected with an end of said first-mentioned means for turning the latter so as to wind the collapsed end of said tube therearound either with said cap mounted on the dispensing head of said tube or removed therefrom.

2. A device of the character described comprising a collapsible tube having a dispensing head mounted on one end thereof, the opposite end of said tube being collapsed and having a portion cut out of one side thereof, a spindle having a longitudinal slot extending therein receiving the collapsed end of the tube and including a portion disposed within the cut out portion of said collapsed tube end so that the latter can be rolled on said spindle, said spindle portion having a longitudinally extending aperture formed therein, a cap removably mounted on said tube head, said cap having an aperture extending longitudinally therein and terminating short of the interior thereof, and a spindle rotating element forming a longitudinal extension of said cap and having a projection extending in said cap aperture and removable therefrom for insertion in said spindle aperture to turn the latter and hence roll the tube thereon. 10 15

3. A device as defined in claim 2 wherein said projection comprises a threaded stem and wherein said cap aperture and said spindle aperture are both threaded to receive said stem. 20

4. A device as defined in claim 2 wherein said projection comprises a bar having an angular cross-sectional configuration and wherein said cap aperture and said spindle aperture both have a shape corresponding to the 5 shape of said bar.
